US00D495263S1

(12) **United States Design Patent** (10) Patent No.: **US D495,263 S**
Liao (45) Date of Patent: **** Aug. 31, 2004**

(54) **LEVELING DEVICE**

(75) Inventor: **Wen-Hsin Liao, Ta Li (TW)**
(73) Assignee: **Ching Lin Industrial Co., Ltd., Ta Li (TW)**
(**) Term: **14 Years**
(21) Appl. No.: **29/192,316**
(22) Filed: **Oct. 22, 2003**
(51) LOC (7) Cl. **10-04**
(52) U.S. Cl. **D10/69**
(58) Field of Search **D10/69, 65, 74; 33/285, 286, 290, 291, 292, 227, 348, 348.2, 379-383; 356/247, 248, 249, 250, 138**
